UNITED STATES PATENT OFFICE

140,127

DESIGN FOR AN AIRPLANE

Michael Watter, Philadelphia, Pa., assignor to
Edward G. Budd Manufacturing Company,
Philadelphia, Pa., a corporation of Pennsylvania

Application April 21, 1944, Serial No. 113,329

Term of patent 14 years

(Cl. D71—1)

To all whom it may concern:

Be it known that I, Michael Watter, a citizen of the United States, residing at Philadelphia, in the county of Philadelphia and State of Pennsylvania, have invented a new, original, and ornamental Design for an Airplane, of which the following is a specification, reference being had to the accompanying drawings, forming a part thereof.

In the drawings:

Fig. 1 is a three-quarter perspective view of an airplane showing my new design, as seen from the front;

Fig. 2 is a similar view thereof as seen from the rear.

Fig. 3 is a perspective view thereof as seen from the left-hand side;

Fig. 4 is a plan view thereof;

Fig. 5 is a straight-on front perspective view thereof; and

Fig. 6 is a similar rear perspective view thereof.

This application is a continuation-in-part of my design application S. N. D-107,597 for "Airplane," filed July 18, 1942.

I claim:

The ornamental design for an airplane, substantially as shown.

MICHAEL WATTER.
